William A. Baum, Forest Hills, N. Y., assignor to
W. A. Baum Co., Inc., New York, N. Y., a cor-
poration of New York

Application April 12, 1939, Serial No. 84,240

Term of patent 14 years

To all whom it may concern:

Be it known that I, William A. Baum, a citizen
of the United States, residing at Forest Hills, in
the county of Queens and State of New York, have
invented a new, original, and ornamental Design
for a Pedestal Sphygmomanometer, of which the
following is a specification, reference being had
to the accompanying drawing, forming part
thereof.

Fig. 1 is a side view, and

Fig. 2 is a front view of a pedestal sphygmo-
manometer, showing my new design.

I claim:

The ornamental design for a pedestal sphygmo-
manometer, substantially as shown.

WILLIAM A. BAUM.
